DESIGN FOR A CASING FOR COIN OPERATED GAME

Everett B. Eckland, Oak Park, Ill., assignor of one-half to James T. Mangan, Chicago, Ill.

Application September 17, 1945, Serial No. 122,129

Term of patent 14 years

(Cl. D34—5)

To all whom it may concern:

Be it known that I, Everett B. Eckland, a citizen of the United States, residing in the village of Oak Park, in the county of Cook and State of Illinois, have invented a new, original, and ornamental Design for a Casing for Coin Operated Game, of which the following is a specification, reference being had to the accompanying drawing, forming part thereof.

Fig. 1 is front elevation of a casing for coin operated game showing my new design.

Fig. 2 is perspective view thereof.

The side not shown is the same in appearance as the side shown in Fig. 2. The back is open to receive the coin operated mechanism of the game for which the casing shown has been designed. The white spaces on the drawing represent openings or windows for disclosing portions of the coin operated game to be housed within the instant casing.

I claim:

The ornamental design for a casing for coin operated game, as shown and described.

EVERETT B. ECKLAND.
